UNITED STATES PATENT OFFICE.

HENRY HORAN, OF EAST ORANGE, NEW JERSEY.

DESIGN FOR CARPET.

SPECIFICATION forming part of Design No. 11,674, dated March 9, 1880.

Application filed February 12, 1880. Term of patent 34 years.

To all whom it may concern:

Be it known that I, HENRY HORAN, of East Orange, in the county of Essex and State of New Jersey, have invented a new and original 5 Design for Carpet, of which the following is a specification.

This invention relates to a new and original design for carpets, oil-cloths, and similar fabrics.

10 It consists in the novel grouping and configuration of figures hereinafter more fully described.

The accompanying photograph illustrates a face view of a carpet having my new design.

15 The design consists of a group, A, composed of leaves and flowers; a group, B, of leaves and a large open rose; a group, C, of leaves;

a group, D, of leaves and flowers; a spray, E, of leaves, flowers, buds, and branches placed in the center of the field or ground of the carpet and connecting the groups C D, and of a group, F, composed of flowers, leaves, and buds. The sprays and branches of the several groups extend into the field or ground G of the carpet, so as to intermingle and connect the several groups together. 20 25

I claim—

The design for a carpet, consisting of the groups A B C D F and spray E, substantially as shown.

HENRY HORAN.
